UNITED STATES PATENT OFFICE.

RICHARD FRITSCHE, OF LIPPSTADT, GERMANY.

ELECTRICAL SOLDERING DEVICE.

Application filed October 8, 1924. Serial No. 742,311.

To all whom it may concern:

Be it known that I, RICHARD FRITSCHE, a citizen of the German Empire, and residing at Lippstadt, Germany, have invented certain new and useful Improvements in Electrical Soldering Devices, of which the following is a specification.

The invention relates to a device adapted for soldering electrically wires, saw-blades and the like, and in particular for soldering the wires of wire cables. Up to the present time the wires in hoisting and other wire cables were soldered by means of a gas flame, which proved tiresome and unreliable. This drawback is overcome by the new electrical soldering device. In order to be able to quickly regulate the intensity of current according to requirements, according to the present invention the heating of the wire, saw blade or the like to be soldered is effected by means of an alternating current transformer, whose primary coil is subdivided in at least two coils, which can be connected by means of push-buttons in such a way that either only one coil will act solely, or that both or a plurality of primary coils are connected in series or parallelly.

A mode of execution of the device of the kind referred to is represented on the drawing in which

Figure 1 is an elevation,

Figure 2 a side elevation of the clamp, serving for holding the wire,

Figure 3 a top view of the push-button and

Figure 4 a diagram showing the connection of the primary coils.

The secondary coil *w* of the transformer *a* is connected with the supports *b* which are insulated from one another and from the casing. Upon these supports two clamping devices *c* and *d* are mounted and adapted to be adjusted in respect of the wire to be soldered. The clamp *d* is resting immediately on the support *b* and can be adjusted by means of a thumb-nut while the clamp *c* slides upon a base *e* provided with a stop, and it can be fixed by means of a thumb-nut *g* to said support. Two springs engaging the clamp *c* laterally tend to pull the clamps against the stop of the base *e* projecting in an upward direction. Each clamp is provided with a clamping arm *h* which is pressed against the stationary clamping jaw by means of a winged nut *i* against the action of a spring *k* which latter tends to lift

the clamping arm after the release of the winged nut, in order to release the wire.

The primary coil is sub-divided into two coils *u* and *v* (Figure 4), which can be connected differently by means of the push-buttons 1, 2, 3. The push-buttons 1 and 2 are mounted on a lever *l* consisting of insulating material, and on both sides of its axis of rotation *n*. This lever carries upon its disengaged end besides the push button 1 a contact knife *s* adapted to engage a contact *s*¹ of the primary coil. On the opposite end of the lever *l* both the contact knives *p* and *q* are arranged, adapted to engage the contacts *p*¹ and *q*¹ of the primary coil. Generally the lever *l* is held in its inoperative position by means of a spring *t*, in which position none of the contact knives will be in engagement with the pertinent contact.

The push-button 2 is mounted on a one-armed lever *m* carrying on its disengaged end a contact knife *r* which will engage the contact *r*¹ after pressing down the said push-button.

As soon as the push-button 1 is pressed down the contact *s* *s*¹ will be closed. The current supplied from the lead *x* (Figure 4) will then flow through the first primary coil *u*, from thence through the lead *z*¹ to the closed contact *s*, *s*¹, further through the leads *z*⁷ and *z*⁶ to the second coil *v* and through the lead *y* to the other pole. Thus both the coils *u* and *v* are connected in series.

If the push-button 2 is pressed down, the current will flow from the lead *x* through *z*⁴ and *z*⁸ to the contact *r* *r*¹ from thence through *z*⁶ to the coil *v* and from there to the lead *y*. Thus only the coil *v* is cut in.

On pressing down the push-button 3 the current will flow from the lead *x* through the coil *u* and from thence through *z*¹, *z*² to contact *q* *q*¹ and from there through *z*³ to the lead *y*. Another portion of the current will flow from the lead *x* through *z*⁴, *z*⁹ to the contact *p*¹ *p*, from here through *z*⁵ *z*⁶ to the coil *v* and from the latter to the lead *y*. Thus both the coils *u* and *v* are connected parallelly.

The ends of the wires to be soldered together are made oblique and then fixed in the clamps *c* and *d* in such a manner that the oblique ends will fit together. In this instance the clamp *c* must abut with its rear end against the stop of the base *e*. Then a piece of thin brass wire is wound round the

portion to be soldered in order to serve as soldering material, and then according to the diameter of the wire to be soldered one of the push-buttons 1, 2 or 3 is pressed down 5 for the purpose either to cut in only one coil or to connect both coils in series or parallelly. As soon as the wire is sufficiently heated, in any case both coils will be connected in series with the object in view to 10 allow the solder to flow properly and to fill in neatly the space between both ends of wire. Copper wires too, can be soldered with silver solder in the same manner.

The wire will expand under the action of 15 the heat thus causing the oblique ends of wire to be pressed firmly together, since the clamps *c* and *d* cannot recede. After the solder has reached its liquid state, the push-button is released, so that the supply of current is interrupted and the wire allowed to 20 cool down. When it is shrinking again in consequence of the cooling the movable clamp *c* can yield against the action of the springs *f* thus preventing any tugging at 25 the soldered point still warm, through which the uniformity and solidity of the solder would be affected.

I claim:

1. An electric soldering device for wires, 30 saw blades, steel bands and the like, comprising a transformer having a multiple part primary coil and a secondary coil, a centrally pivoted lever, contacts, and electrical connections, whereby when the said lever is moved in one direction it bears against pre-determined contacts to close a circuit through 35 the primary coil with the parts thereof in series, and when the said pivoted lever is

moved in the opposite direction it bears against contacts to close a circuit through the primary coil with the parts thereof in parallel.

2. An electric soldering device for wires, saw blades, steel bands and the like, comprising a transformer having a two part 45 primary coil and a secondary coil, a centrally pivoted lever, contacts, and electrical connections, whereby when the said lever is moved in one direction it bears against pre-determined contacts to close a circuit through 50 the primary coil with the parts thereof in series, and when the said pivoted lever is moved in the opposite direction it bears against contacts to close a circuit through the primary coil with the parts thereof in 55 parallel.

3. An electric soldering device for wires, saw blades, steel bands and the like, comprising a transformer having a two part primary coil and a secondary coil, a centrally pivoted lever, contacts, and electrical 60 connections, whereby when the said lever is moved in one direction it bears against pre-determined contacts to close a circuit through the primary coil with the parts thereof in 65 series, and when the said pivoted lever is moved in the opposite direction it bears against contacts to close a circuit through the primary coil with the parts thereof in 70 parallel, and a second lever pivoted adjacent one end thereof and adapted to bear against contacts to close an electric circuit through one part only of the said primary coil.

In testimony whereof I affix my signature to this specification.

RICHARD FRITSCHE.
